Atty.

UNITED STATES PATENT OFFICE.

MAURICE N. WEINSTEIN, OF EAST CLEVELAND, OHIO.

CLEANER AND GAUGE FOR WINDING MACHINES.

Application filed April 14, 1921. Serial No. 461,403.

To all whom it may concern:

Be it known that I, MAURICE N. WEINSTEIN, a citizen of the United States, residing at East Cleveland, in the county of Cuyahoga and State of Ohio, have invented a certain new and useful Improvement in Cleaners and Gauges for Winding Machines, of which the following is a full, clear, and exact description, reference being had to the accompanying drawings.

This invention is a novel construction of cleaner and gauge used in connection with machines for winding wool, silk or other material, and the object of the invention is to provide an exceedingly cheap and simple device which is capable of accurate adjustment, one which can be quickly and easily attached to any of the various types of machines now in use and one which will be more durable than the cleaners now employed.

It is well known that wool, silk and similar material, as manufactured, contains certain imperfections either in the way of foreign matter adhering to the threads, or excess of material at certain points and inasmuch as a uniform dimension of thread or strand is desired in knitting and weaving, it is customary in winding the strand to clean or scrape the same so as to remove all surplus or foreign matter so that the thread or strand as finally wound, will be of uniform dimension. While cleaners or scrapers have been employed in connection with various types of winding machines, they have proven only partially successful, owing to the difficulty of accurate adjustment and for various other reasons. As before stated, the object of my invention is to provide a simple and improved device which will remedy these various defects.

With these objects in view my invention consists in the novel features of construction and in the manner of combining or arranging the same, all of which will be hereinafter fully described and set forth in the appended claims.

In the drawings forming a part of this specification, Fig. 1 is a face view of one form of cleaner embodying my invention;

Fig. 2 is a side view of the same; Fig. 3 is a longitudinal sectional view on the line 3-3

of Fig. 2; Fig. 4 is a transverse sectional view on the line 4-4 of Fig. 1 and Fig. 5 is a transverse sectional view on the line 5-5 of Fig. 1. In the practical embodiment of my invention, I employ an arm A which is connected to any suitable portion of the machine frame A' and it will be understood that this arm A can be arranged either vertically, or horizontally and can be either straight or bent, it being intended only as a carrier and means of attachment for connecting my improved cleaner in its proper position with reference to the machine frame. The cleaner proper embodies a pair of blocks B and C to which are connected the cleaner blades D and E, respectively. The block B is rigidly connected to the arm or rod A through the medium of a screw or bolt F and it will be understood that the arm or rod A may enter the block B from the end as shown in the drawings; or it can be entered at the side. The rod or arm A, being rigidly connected to the machine frame and the block B being connected thereto, the block C is adjustably connected to the block B through the medium of an adjusting screw G which passes through the block C and screws into the threaded bore G' of the block B. A coil spring H surrounds the screw G and is held in the counterbored portions of the openings through which the screw passes, the tendency of the spring being to force the block C away from the block D and the screw G is provided with a head G² which sets in a counterbored recess in the face of the block C. It is obvious that by turning the screw in the desired direction the block C can be caused to move toward or away from the block B. The head G² of the screw is provided with graduations and the face of the block C is also graduated so that by turning the screw a definite amount in either direction, a definite and accurate movement of the block C can be obtained.

In order to guide the block C in its movements and insure parallelism at all times, I employ a guide finger I which is rigidly connected to the block C and projects laterally therefrom and is preferably square in cross section as shown, said finger sliding in a guideway K cut in the block D as most

clearly shown. The hardened steel blades D and E are connected to the front faces of the blocks B and C by means of set screws D' and E', respectively, and the blade D is provided with an elongated opening or slot D² through which a set screw L passes into the threaded bore I' produced in the guide finger I, this set screw being tightened after the blades have been adjusted to the desired position by turning the screw G in the proper direction, and it will of course be understood that previous to any adjustment it will be necessary to loosen the set screw L. The front faces of the blocks B and C are planed off from end to end, leaving stop flanges B' and C', respectively, along the outer edges thereof and against which the blades D and E are positioned before tightening up the screws D' and E', respectively. The blocks B and C are also provided with opposed recesses or bores B² and C², respectively, to receive the glass or porcelain roller M over which the yarn or silk travels as it passes between the cleaning blades D and E. It will be noted that there is sufficient clearance between the roller and the bores so that said roller will turn freely in the blocks in contradistinction to being held rigidly as heretofore. This construction not only provides for an increased life of the roller, but also insures easier operation of the device as a whole and also permits the roller to be quickly and easily removed in case of breakage or impairment and the substitution of a new roller. The block B is preferably made longer than the block C and the blade D is also preferably made longer than the blade E. In practice I prefer to cut away the end of the blade E adjacent the blade D, as most clearly shown at E², and also round off the end of the blade E as shown at E³. Shaping the blade E in this manner facilitates the introduction of the yarn, thread or strand, into the space between the cleaning blades, and this relative arrangement of the blade ends is the same, irrespective of whether the blades project downwardly as shown, or upwardly or horizontally. While I have shown the set screw L as applied to the longer block and blade, it will, of course, be understood that it can also be applied, if desired, to the shorter block and blade. In practice, I also prefer to cut away the front face of the guide finger I as indicated at I² in Fig. 4 so that the gauge strip can be readily inserted between the blades when desired, as without this cut away portion the gauge strip could not be fully inserted between the edges of the blades adjacent their upper ends. It is also preferred to provide the head G² of the screw G with openings G³ so spaced as to receive the lugs of an adjusting key (not shown) carried by the master mechanic, so that the screw cannot be tampered with by

the operator of the machine, it being desirable to have the blades set by the master mechanic only and not interfered with by anyone.

It will thus be seen that I provide an exceedingly cheap and simple device which can be quickly and easily connected to any of the present types of winding machines. It will also be noted that the device is capable of quick and easy adjustment by simply loosening the set screw L and turning the screw G in the desired direction, and by means of graduations upon the screw head and the side of the block, a definite amount of movement can be insured by a definite movement of the screw head.

Furthermore, parallelism of movement is obtained through the medium of the guide finger I and by virtue of the stop flanges at the sides of the blocks, absolutely accurate positioning of the blades with reference to said blocks is always assured. By means of the free running glass or porcelain roller the wear upon the roller is reduced to a minimum and the free and easy passage of the yarn or strand between the blades is facilitated.

Should any of the parts become broken or impaired, they can be quickly and easily removed and new ones substituted. The blades, if desired, can be made reversible.

Having thus described my invention, what I claim is:

1. In a device of the kind described the combination with a fixed member having a recess, of a movable member, a screw passing through the movable member and engaging the fixed member and a spring surrounding said screw and bearing upon the contiguous faces of both members, a guide rigidly connected to the movable member and working in a recess produced in the fixed member, blades attached to the fixed and movable members, the blade of the fixed member being slotted and a set screw passing through the slot of said blade and engaging the guide in the fixed member.

2. A device of the kind described comprising a fixed member and a movable member each of said members being recessed and a freely movable guide roller held within the recessed members, a screw passing through one member and engaging the other and a spring surrounding said screw and bearing upon said members, a guide attached to one member and working in the other member, blades attached to the faces of said fixed and movable members, one of said blades being slotted and a set screw working through said slot and engaging the guide held in said member.

3. In a device of the kind described the combination with a support, of a member connected to said support, a second member arranged parallel with the first named mem-

ber, a roller held between said members, a screw passing through the second named member and engaging the first named member, a spring arranged upon said screw and between the members, a guide carried by one member and working in a recess in the other member, and blades connected to the for-

ward faces of said members, the edges of said blades being arranged in close proximity to each other. ¹⁰

In testimony whereof, I hereunto affix my signature.

MAURICE N. WEINSTEIN.
